UNITED STATES PATENT OFFICE.

LEWIS E. WATERMAN, OF ROCKFORD, ILLINOIS, ASSIGNOR TO EMERSON MANUFACTURING COMPANY, OF ROCKFORD, ILLINOIS.

WHEELED PLOW.

SPECIFICATION forming part of Letters Patent No. 705,628, dated July 29, 1902.

Application filed October 13, 1900. Serial No. 32,935. (No model.)

To all whom it may concern:

Be it known that I, LEWIS E. WATERMAN, a citizen of the United States, residing at Rockford, in the county of Winnebago and State 5 of Illinois, have invented certain new and useful improvements in Wheeled Plows, of which the following is a specification.

The object of this invention is to liberate the caster-wheel of a wheeled plow by a connection between the evener and the latch holding the caster-wheel in line.

In the accompanying drawings, Figure 1 is a side elevation of so much of a wheeled plow necessary to show the connection of my improvements therewith. Fig. 2 is an isometrical representation of the forward portion of a plow-beam and my improvements in connection therewith. Fig. 3 is an isometrical representation of the forward portion of a 15 plow-beam and clevis, the clevis turned to one side of the direct line of draft. Fig. 4 is a plan view of the parts in their working position. Fig. 5 is a plan view in which the clevis is turned and the caster-wheel support shown turned in dotted lines. Fig. 6 is a lengthwise vertical section through the bracket supporting the caster-wheel.

The plow-beam 1 supports a plow 2, and a 20 caster-wheel 3 has a connection with its support 4, which is pivotally mounted in a bracket 18, secured to the plow-beam. To the caster-wheel support is secured a segment 5, having a notch in its periphery and held in place by the set-screw 19. A latch 6 has a pivotal connection with the bracket 18 and is adapted to enter the notch in the segment. A spring 20, located in a recess formed in the bracket 18, bears against the latch and holds the latch in the notch of the segment.

To the forward end of the plow-beam are 25 secured two side plates 8 of a clevis, having the series of holes 9 for the vertical adjustment of the horizontal plate 10 in connection

therewith. This horizontal plate has a series of holes 11 for the lateral adjustment of the 45 evener-clevis 12, to which the evener 13 is pivotally connected.

The evener-clevis has a depending projection 14, and from its lower end extends a cross-bar 15. A yoke 16 has its ends pivotally connected to the cross-bar 15, and its upper end supports a hook 17, with which the forward end of the rod 7 has a pivotal connection. The arms of the yoke rest against the face of the horizontal plate 10 when the 55 line of draft is in the lengthwise direction of the plow-beam, which will allow the latch 6 to hold the caster-wheel in proper position for plowing. When it is desired to turn a corner, the team will move the evener-clevis 60 12 upon its pivotal connection with the horizontal bar 10 and laterally of the plow-beam, which will hold one arm of the yoke against the horizontal bar of the clevis and move the other arm away from the horizontal bar 65 15 and at the same time cause the upper portion of the yoke to move forward, drawing on the rod 7 and moving the latch 6 from its connection with the caster-wheel support and permit the wheel to cast. This movement of the yoke will take place when the 70 team moves the clevis to either side of the direct line of draft.

I claim as my invention—

In a wheeled plow, the combination of a 75 plow-beam, a caster-wheel, means for holding the caster-wheel in proper position for plowing, an evener-clevis having a connection with the plow-beam, a yoke pivotally supported by the evener-clevis and a connection between the yoke and the holding means of the caster-wheel.

LEWIS E. WATERMAN.
